PRODUCTION OF SOLID CARBON DIOXIDE

Joseph R. Chamberlain, York, Pa., assignor to
York Ice Machinery Corporation, York, Pa., a
corporation of Delaware

Application December 16, 1930, Serial No. 502,803

13 Claims. (Cl. 62—121)

This invention relates to the production of solid carbon dioxide or CO_2 snow, and particularly to means for condensing and cooling the carbon dioxide prior to expansion thereof in the 5 expansion or snow chamber. It is axiomatic that the percentage of snow yield from the expansion of liquid CO_2 is increased by subtraction of sensible heat of the liquid prior to expansion. Usually this is done by passing the liquid CO_2 10 through coolers in heat interchanging relation with flash gas from the snow chamber. The pressure of the liquid CO_2 in the last cooling stage is generally rather high, however, necessitating compression of the gas through several 15 stages.

In the present invention the condensation and subcooling of the carbon dioxide are effected by independent refrigeration circuits, that is, circuits employing a medium other than flash gas 20 from the main circuit. Specifically, the CO_2 gas, after being compressed to a moderately high pressure, is condensed in an interchanger in heat exchanging relation with ammonia evaporating at a relatively low pressure, after which 25 the resulting liquid is subcooled in an interchanger in heat exchanging relation with evaporating liquid CO_2 in an auxiliary CO_2 circuit, the latter being independent of and not communicating with the main circuit.

Ammonia, having a relatively high critical 30 temperature is condensable within the temperature range of available and normal water supply, whereas carbon dioxide, the critical temperature of which is relatively low, requires for condensation a relatively low temperature. The arrangement of the present apparatus is such 35 that the condensing load is carried entirely by water so that, regardless of the water supply, the condensers and subcooler will function under varying and extreme weather conditions.

As stated hereinbefore, snow yield is increased 40 by extracting sensible heat from liquefied carbon dioxide in the circuit wherein solidification is effected. By employing CO_2 in the subcooling 45 circuit there is obtained a heat exchange in which temperatures corresponding with those produced by flashing of the CO_2 in the snow chamber are attained in the cooling circuit. The 50 temperature of the liquefied CO_2 prior to flashing is thus reduced substantially to that of solidification, that is, to the lowest temperature practicable while retaining the CO_2 in its liquefied state.

Reference is had in the following description 55 to the appended drawing illustrating diagram-

matically the arrangement and relation of the several circuits.

In the drawing, carbon dioxide gas from any suitable source is conducted through pipe 10 to a suction trap 11 and thence to the intake of compressor 12 in which the gas is compressed to about ninety pounds gage. The compressed gas then passes through an interstage cooler 13, preferably water cooled, to a dehumidifier 14 through which flash gas from the expansion chamber is passed and wherein moisture is removed from the gas. From the dehumidifier the carbon dioxide is taken to a second stage compressor 15 in which the pressure is increased to approximately four hundred pounds gage, 10 passed through a second cooler 16, preferably water cooled, and then to a drier 17, which, in the present instance, is a receiver containing calcium chloride, by which practically all of the 15 moisture present in the gas is removed. 20

The compressed and dried gas is now liquefied in a condenser 18, the condensing medium in the present instance being evaporating liquid ammonia. The ammonia circuit will be described in more detail hereinafter. Having been 25 liquefied the carbon dioxide flows to a receiver 19, thence through the tubes of a shell and tube subcooler 21 to expansion chamber 22, the expansion of the liquefied gas being controlled by an expansion valve 23. The shell of subcooler 21 forms the evaporator of an auxiliary CO_2 refrigerating circuit, which will be later described, while the CO_2 in the main circuit passes through the tubes of the subcooler. As the carbon dioxide flows from an expansion nozzle in chamber 22, a portion thereof solidifies, forming a snow-like substance, while the remainder, or flash gas, is returned to the compressor through pipes 24, 25 and 26, the latter two pipes being in communication with suction trap 11 directly, and indirectly, through dehumidifier 14 respectively. By means of valves 27, 28 the proportion of returned gas passed to the suction trap directly, and indirectly through the shell of the dehumidifier 14, may be controlled. 30

The auxiliary or subcooling CO_2 circuit comprises a compressor 29 which takes gas from suction trap 31 at about ninety pounds gage and compresses it to approximately four hundred pounds gage. The compressed gas then flows through a water cooled heat interchanger 32 and through the tubes of condenser 18 to receiver 33. From the receiver the CO_2 , now in liquid form, is admitted to suction trap 31 and the connected shell 21 of the sub-cooler, the 35 40 45 50 55

flow thereto being regulated by a low-side float valve 34. The liquid CO₂ evaporated in the shell of subcooler 21 returns to compressor 29 to be recompressed.

- 5 The condensing circuit is similar to the sub-cooling circuit except that, in the present instance, ammonia is employed as the refrigerating medium. Ammonia is compressed by compressor 35 and liquefied in a water cooled condenser 36 from which it flows to receiver 37. The liquefied ammonia, after being admitted to suction trap 38 through a low-side float valve 39, evaporates in the connected evaporator shells of condensers 18 and 18', the resulting drop in 10 temperature being sufficient to liquefy compressed carbon dioxide in the main as well as in the auxiliary CO₂ circuits. The evaporated ammonia is returned to compressor 35 for re-compression. The condensers 18 and 18' are 15 preferably arranged as shown in the drawing. Each of the condensers is a shell and tube interchanger, the shells being connected by relatively large pipes 40 so that the shells of the condensers are connected to form a single evaporator. The 20 CO₂ circuits are, obviously, separated, the tubes in the respective condensers communicating with separate headers.

The operation of the apparatus is obvious from the foregoing description. The ammonia circuit is employed to condense CO₂ gas at moderately high pressure in both the main and sub-cooling circuits. The subcooling circuit employs a refrigerating medium operating efficiently at higher pressure than the ammonia circuit 35 and capable of producing lower temperatures in its evaporator upon expansion. The last-mentioned evaporator forms part of a subcooling interchanger designed to remove a substantial amount of sensible heat from the liquefied 40 CO₂ in the main circuit prior to its expansion in the snow chamber, thus insuring a relatively high yield of CO₂ snow.

It is apparent that the herein described apparatus has decided advantages in that it is only 45 necessary to compress the carbon dioxide to moderately high pressures, that interchangers are not dependent on the flash gas or circuits bled from the main circuit, and that primary condensation is effected by water, the temperature 50 of which is relatively unimportant. By the last statement is meant that the ammonia circuit uses water for condensing, while the refrigerating mediums employed in the other circuits are liquefied by expansion of the ammonia 55 previously condensed by water. This arrangement, therefore, provides for efficient cooling of the refrigerants in each circuit, regardless of available water temperatures, it being necessary only to vary the speeds of the compressor to 60 regulate the temperatures in the condensers and subcooler. As a result, there is obtained economical condensation of the compressed gas and extraction of a substantial portion of the sensible heat of the liquefied carbon dioxide before expansion in the snow chamber.

The apparatus is illustrated diagrammatically and is not intended to limit the relation of the several constituents thereof or restrict the invention to the specific refrigerants referred to 70 in the foregoing description.

What is claimed is:—

1. In combination, a main closed refrigeration circuit in which carbon dioxide is circulated and to which additional carbon dioxide is supplied; a 75 second closed refrigeration circuit in which a re-

frigerant is expanded to extract heat from liquid carbon dioxide in the main circuit; a third closed refrigeration circuit in which a refrigerant is expanded to liquefy compressed gases in said second circuit; and means for expanding liquefied carbon dioxide in the main circuit to form carbon dioxide snow.

2. In apparatus for solidifying carbon dioxide, a main closed refrigeration circuit for the carbon dioxide; a second closed refrigeration circuit in which a refrigerant is expanded to extract heat from liquid carbon dioxide in the main circuit; and a third closed refrigeration circuit in which a refrigerant is expanded to liquefy compressed gases in said main and second circuits.

3. In combination, a main closed refrigeration circuit in which carbon dioxide is circulated and to which additional carbon dioxide is supplied; a second closed refrigeration circuit in which carbon dioxide is expanded to extract heat from liquid carbon dioxide in the main circuit; a third closed refrigeration circuit in which a refrigerant is expanded to liquefy compressed gases in said second circuit; and means for expanding liquefied carbon dioxide in the main circuit to form carbon dioxide snow.

4. In combination, a main closed refrigeration circuit in which carbon dioxide is circulated and to which additional carbon dioxide is supplied; a second closed refrigeration circuit in which a refrigerant is expanded to extract heat from liquid carbon dioxide in the main circuit; a third closed refrigeration circuit in which ammonia is expanded to liquefy compressed gases in said second circuit; and means for expanding liquefied carbon dioxide in the main circuit to form carbon dioxide snow.

5. In combination, a main closed refrigeration circuit in which carbon dioxide is circulated and to which additional carbon dioxide is supplied; a second closed refrigeration circuit in which carbon dioxide is expanded to extract heat from liquid carbon dioxide in the main circuit; a third closed refrigeration circuit in which ammonia is expanded to liquefy compressed gases in said second circuit; and means for expanding liquefied carbon dioxide in the main circuit to form carbon dioxide snow.

6. In an apparatus for solidifying carbon dioxide, a plurality of refrigeration circuits of the compression-condensing-expansion type, one of said circuits containing the carbon dioxide to be solidified, another of said circuits containing carbon dioxide and disposed in heat exchanging relation with liquefied carbon dioxide in said first-mentioned circuit, and a third of said circuits containing ammonia in heat exchanging relation with said other circuits.

7. In combination, a main refrigeration circuit in which carbon dioxide is circulated and to which additional carbon dioxide is supplied; a second refrigeration circuit in which a refrigerant having a relatively low critical temperature is expanded to extract heat from liquid carbon dioxide in the main circuit; a third refrigeration circuit in which a refrigerant having a relatively high critical temperature is expanded to liquefy compressed gases in said second circuit; and means for expanding liquefied carbon dioxide in the main circuit to form carbon dioxide snow.

8. In apparatus for solidifying carbon dioxide, a main refrigeration circuit for the carbon dioxide; a second refrigeration circuit in which a

refrigerant having a relatively low critical temperature is expanded to extract heat from liquid carbon dioxide in the main circuit; and a third refrigeration circuit in which a refrigerant having a relatively high critical temperature is expanded to liquefy compressed gases in said main and second circuits.

9. In combination, a main refrigeration circuit in which carbon dioxide is circulated and to which additional carbon dioxide is supplied; a second refrigeration circuit in which a refrigerant condensable by heat exchange with water is expanded to condense carbon dioxide in said main circuit; a third circuit in which a refrigerant condensable by heat exchange with expanded refrigerant in said second circuit is expanded to cool liquefied carbon dioxide in said main circuit; and means for expanding liquefied carbon dioxide in the main circuit to form carbon dioxide snow.

10. In an apparatus for solidifying carbon dioxide, a plurality of refrigeration circuits, each including a compressor, a condenser and an expansion chamber, one of said circuits containing the carbon dioxide to be solidified, a second of said circuits containing a refrigerant having a relatively low critical temperature, and a third of said circuits containing a refrigerant having a relatively high critical temperature, the expansion chamber of said last-mentioned circuit forming part of a heat exchanger through which the refrigerants in said other circuits flow and are liquefied, the expansion chamber of said second-mentioned circuit forming part of a heat exchanger through which liquefied carbon dioxide in the main circuit flows.

11. The method of solidifying carbon dioxide which comprises the steps of compressing, liquefying, subcooling and expanding the carbon di-

oxide to form snow, the compressed carbon dioxide being liquefied by subjection thereof to heat exchange with an expanded refrigerant, the latter being condensable by heat exchange with water, and the subcooling being effected by subjection of the liquefied carbon dioxide to heat exchange with a refrigerant condensable by heat exchange with said expanded refrigerant.

12. The method of solidifying carbon dioxide which comprises the steps of compressing, liquefying, sub-cooling and expanding the carbon dioxide to form snow, the compressed carbon dioxide being liquefied by subjection thereof to heat exchange with an expanded refrigerant, the latter being condensable by heat exchange with water, and the sub-cooling being effected by subjection of the liquefied carbon dioxide to heat exchange with a refrigerant capable of cooling the liquefied carbon dioxide to substantially its freezing temperature.

13. The process for producing solid carbon dioxide, which comprises compressing carbon dioxide gas, liquefying the compressed gas by cooling, then sub-cooling such liquid under the pressure of compression and liquefaction, then expanding the sub-cooled liquid to form solid carbon dioxide and flash gas; such sub-cooling being performed by expansion of carbon dioxide gas in an independent refrigerating circuit in which carbon dioxide is repeatedly compressed, liquefied by cooling, and expanded; the cooling for liquefaction in each of the two instances aforesaid being performed by the expansion of a refrigerant having a higher critical temperature than carbon dioxide, in a refrigerating circuit in which said refrigerant is repeatedly compressed, liquefied by cooling, and expanded.
